UNITED STATES PATENT OFFICE.

RICHARD HOPE PURNELL, OF ROSEDALE, MISSISSIPPI.

CULTIVATOR.

1,045,080.

Specification of Letters Patent. Patented Nov. 19, 1912.

Application filed March 23, 1912. Serial No. 636,832.

To all whom it may concern:

Be it known that I, RICHARD H. PURNELL, a citizen of the United States, and a resident of Rosedale, in the county of Bolivar and State of Mississippi, have invented an Improvement in Cultivators, of which the following is a specification.

The object of my invention is to provide an improved cultivator, especially one adapted for use as a cotton-scaper, harrow, or other analogous implement.

To this end, I provide a main draft-beam with two attachments, one being a supplemental pivoted beam carrying a scraper or other cultivating device and adapted to swing laterally, to vary the lateral angle or inclination of the scraper; and the other attachment is a runner and gage arranged in rear of the supplemental beam and adapted for vertical adjustment, to vary the depth at which the scraper or other tool shall enter the soil.

In the drawing Figure 1 is a side view of my invention. Fig. 2 is a longitudinal vertical section of the same. Fig. 3 is a vertical cross section on the line 3—3 of Fig. 1. Fig. 4 is a vertical section on the line 4—4 of Fig. 1.

The numeral 1 indicates the main beam, 2 the supplemental beam arranged under, and parallel with, said main beam, and pivoted thereto and provided with a curved pendent stock, or foot, adapted for attachment of a scraper 3, or other cultivating device. The depth gage is arranged in rear of the supplemental beam and comprises a runner 4 which is arranged horizontally and parallel to the main beam and adapted for vertical adjustment relative thereto. The details of construction, arrangement, and operation of the two attachments will now be described.

The main beam 1 is constructed of angle iron for the sake of combining lightness, strength, and rigidity in the highest degree. The supplemental, scraper-carrying beam 2, is pivoted at its ends in attachments of the main beam, the forward attachment consisting of an L-shaped bracket 5 which may be cast integral with the clevis 6 and is secured to the main beam by the same bolt 7. The rear end of the supplemental beam 2 is pivoted in a pendent flange 8 formed on the head 9 of the hollow guide 10 in which a post 11, forming a fixed portion of the runner 4, is adapted to slide. The head of

the guide 10 is secured to the beam by bolts 12. Thus, the front and rear attachments of the main beam serve as the means for pivoting and supporting the supplemental beam 2; and in both cases the attachments lie in contact with both flanges of the main beam.

As illustrated in Fig. 3, the supplemental beam is adapted to swing so that the scraper 3 or other attached device may be swung laterally to vary its angle to the surface over which the implement is drawn. For effecting such adjustment and for holding the scraper or other tool rigidly in any position to which it may be adjusted, I provide the stop or foot with a lateral arm 13, and the main beam 1 with an upwardly curved and lateral arm 14, and connect the two by means of a turn-buckle 15. It is apparent that by adjusting, that is to say, rotating, the turn-buckle, the angle or inclination of the lateral arm 13 will be varied and the scraper 3 thereby adjusted at a greater or less lateral inclination, as will be seen by comparison of full and dotted lines in Fig. 3.

The vertical adjustment of the depth gage 4 is also effected by means of a turn-buckle 16 which connects it with an angular bracket 17 secured on the upper side of the main beam 1. It will be seen that the post 11 being rigid with the runner 4 will hold it in the same plane with the beam 1 and in order to prevent its rotation on the axis 11, the latter is provided with a cross-pin 11^a—see Fig. 4—which works in slots 10^a formed in the pendent guide 10. Thus by adjusting, that is to say, rotating the turn-buckle, the runner may be adjusted higher or lower without otherwise affecting its relation to the main beam or the supplemental beam. It will thus serve as a depth gage and as a support for the rear portion of the implement taken as a whole.

In order to prevent the runner from skidding or sliding laterally, it is provided along one edge with a downwardly projecting longitudinal rib or flange 4^a—see Figs. 2 and 4.

What I claim is:

1. The combination with a main beam, of a supplemental beam pivoted beneath and parallel to the former and having a cultivating device attached, both beams being provided with lateral arms on the same side, and a turn-buckle connecting the free ends of said arms, as described.
2. The combination with a main beam and

1,045,080

a supplemental beam provided with a cultivating device, of a depth gage comprising a runner arranged in rear of the cultivating device, a tubular guide pendent from the main beam, a rigid attachment of the runner adapted to slide in said guide, and a turn-buckle connecting the runner with the main beam, as described.

3. The combination with a main beam and a supplemental beam having a foot adapted for attachment of a scraper or other cultivating device, of a depth gage forming an attachment of the main beam and rear of

the supplemental one, and consisting of a tubular guide rigidly attached to the beam 15 and pendent therefrom, a runner having a post adapted to slide in the tubular guide and prevented from rotation therein, and a turn-buckle connecting the runner with the main beam and serving for adjustment of 20 the runner higher or lower, as shown and described.

RICHARD HOPE PURNELL.
